UNITED STATES PATENT OFFICE.

FREDERIC CLARKE SHOBERT, OF PITTSBURG, PENNSYLVANIA.

COPY-HOLDER.

No. 831,385.

Specification of Letters Patent.

Patented Sept. 18, 1906.

Application filed November 25, 1905. Serial No. 289,027

To all whom it may concern:

Be it known that I, FREDERIC CLARKE SHOBERT, a citizen of the United States of America, residing at Pittsburg, in the county of Allegheny and State of Pennsylvania, have invented certain new and useful Improvements in Copy-Holders, of which the following is a specification, reference being had therein to the accompanying drawings.

10 This invention relates to certain new and useful improvements in copy and manuscript holders, and the invention relates more particularly to a holder adapted to be used by stenographers and type-writers when copying manuscript.

The invention has for its primary object the provision of novel means for adjustably supporting manuscript; also novel means whereby each line of the manuscript may be 20 closely followed. To this end I have devised a copy or manuscript holder adapted to be mounted upon the desk or table where it is used, and I have constructed my improved copy-holder whereby it can be adjusted to hold the manuscript at any desired angle 25 visible to the eye of the person copying or using the same. I have also constructed the holder whereby it may be used as a book holder or support for reading purposes, and throughout the entire construction of the holder I have embodied certain novel features of construction which permit of the holder being manufactured at a comparatively small cost.

30 The entire holder or structure is preferably constructed of pressed sheet metal, and the detail construction of the same, together with other objects which will hereinafter appear, will be described; but reference will 40 first be had to the accompanying drawings, wherein like numerals of reference designate corresponding parts throughout the several views, in which—

Figure 1 is a front elevation of my improved copy-holder. Fig. 2 is a side elevation of the same. Fig. 3 is a side elevation of the holder detached from the main supporting-standard and positioned to support and retain a book or manuscript. Fig. 4 50 is a detail view of the upper end of a movable standard used in connection with the main supporting-standard, illustrating the manner in which the movable standard is sheared or cut. Fig. 5 is a similar view illustrating the completed upper end of the movable standard. Fig. 6 is a plan of the

same. Fig. 7 is a plan of the retaining-band used in connection with the movable standard. Fig. 8 is a front elevation of the same; Fig. 9, detail views of a pivotal connection 60 formed between the standard and the copy-holder proper. Fig. 10 is a plan of the screw used with the pivotal connection. Fig. 11 is a plan of the base of the standard. Fig. 12 is a side elevation. Fig. 13 is a detail view 65 of the end of the main standard. Fig. 14 is a sectional view taken on the line $x-x$ of Fig. 13. Fig. 15 is an edge view of a clamp.

To put my invention into practice, I construct my improved copy or manuscript holder of two parts—a manuscript-supporting member 1 and a standard 2, these parts being pivotally connected together, as at 3. The member 1 is constructed of two plates 4 and 5, the plate 4 being slidably mounted 70 upon the plate 5. These plates are substantially triangular in form, having curved converging edges 6 and 7, the edges 6 of the plate 5 converging to a tongue 8, having a longitudinally-disposed slot 9 formed there- 75 in. The lower end of the plate 4 is bent downwardly, as at 10, and slotted, as at 11, to receive the tongue 8 of the plate 5. The plate 4 is provided at its lower end with an adjustable screw 12, which extends down- 80 wardly through the slot 9 of the tongue 8, and said screw is adjusted to lock the plate 4 upon the tongue 8 of the plate 5 in any de- 85 sired position. By simply gripping the screw 12 and rotating it slightly the plate 4 90 can be adjusted and then fixed relative to the plate 5.

The lower edge of the plate 5 is bent upwardly, as at 14, and then at an angle, as at 15, forming a bracket 16, which has its outer 95 edges slotted, as at 17 17. Mounted upon said bracket is a set of pivotally-connected levers 18, said levers being arranged similar to a pair of "lazy-tongs." The ends 19 19 of the "lazy-tongs," as they will be herein- 100 after termed, are slidably mounted in the slots 17 17 of the bracket 16, while the upper ends 20 20 of said tongs are slidably mounted in slots 21 21, formed in an angular metallic follower 22, the upper edge 23 of said 105 follower being adapted to bear upon the manuscript mounted upon the plates 4 and 5.

A conventional form of clamp 24 may be used in connection with the top edge of the plate 4 to hold a manuscript or copy upon the plates 4 and 5, said clamp being illus- 110 trated in Fig. 15 of the drawings. When a

manuscript is placed upon the member 1, the upwardly-bent edge 14 of the plate 5 is adapted to support the lower edges of the manuscript, while the clamp 24 will firmly hold the upper edge of the manuscript while the follower 22 is being moved over said manuscript or copy.

The rear face of the plate 5 is provided with two outwardly-extending pierced lugs 25 25, 10 and pivotally mounted between said lugs by an adjustable screw or bolt 26 is the contracted pierced end 27 of the main standard 28. The contracted pierced end 27 of said standard, together with the lugs 25 25, are 15 made of a sufficient size to provide a frictional surface between the end of the standard 28 and said lugs, the screw or bolt being adapted to govern the friction that exists between the end 27 and the lugs 25 25 and hold 20 the member 1 in any desired position relative to the standard 2.

The main standard 28 is angular in form, as it will be observed, and this standard is adapted to slide into a movable standard 29, 25 which in turn is slidably mounted in a portable yet generally fixed standard 30. The standards are adapted to telescope one within the other, and in order to hold the standards in a fixed position I employ retaining-bands 31 31 and clasps 32 32. In constructing the clasps 32 32 I split, shear, or cut the upper ends of the standards 29 and 30, as indicated at 33, and bend the split edges outwardly to form parallel pierced lugs 34 34. 30 In these lugs is mounted an adjustable screw 35, employed for contracting the upper ends of the standards. When one standard is mounted within the other, the screws 35 are adapted to be adjusted to clamp the upper 35 end of the standard upon the standard which slides into it, and in connection with these 40 clamps the retaining-bands 31 31 are employed for limiting the movement of one standard within another, even though the 45 clamps 32 were not used. The retaining-bands are constructed by splitting a band, as at 36, and bending its ends outwardly to form pierced lugs 37 37, through which a set-screw 38 passes to expand or contract the 50 split ends of the band. The retaining-bands can be secured upon any part of the standards and when clamped upon the standard the retaining-band is adapted to rest upon the end of a standard in which the first-mentioned standard is mounted.

The portable standard 30 is supported by a base 39, said base being pierced, as at 40 40, in order that it may be secured to a desk or table in connection with which it is used. 60 The base 39 is provided with an upwardly-extending split collar 41, similar to the upper ends of the standards heretofore described, a set-screw 42 being employed to clamp the collar upon the lower end of the standard 30. 65 The lower end of the main standard 28 is

split or sheared, as at 43 43, to form lugs 44 44, said lugs being bent inwardly to grip a piece of rubber or resilient material 45, which protrudes out of the end of the standard 28. This piece of rubber or resilient material is 70 employed to prevent the end of a standard 28 from injuring or scarring the polished surface of the desk or table in connection with which it is used when the copy-holder or manuscript-holder is being used in the position shown in Fig. 3 of the drawings, where it is adapted to support a book or manuscript 75 in position convenient to a person copying or reading the same.

By the construction of the numerous parts 80 of the standard 2 it will be observed that the same can be readily disassembled and assembled and in the latter position may be adjusted to retain the member 1 at any desired height and while in the former condition may 85 be packed in a comparatively small space or assembled to be used either in the position shown in Fig. 3 of the drawings or as illustrated in Figs. 1 and 2 of the drawings. In either position the copy or manuscript holder 90 is used for following each and every line of the manuscript or copy, this being accomplished by the person using the same moving the follower 22 as the copying or reading of the manuscript progresses.

The lazy-tongs which I employ for moving the follower may be constructed of resilient and spring steel, whereby the follower will always be pressed in engagement with the manuscript or copy over which it travels, and to facilitate the moving of the follower the same may be provided with a button or knob whereby it can be easily and quickly manipulated.

From the foregoing it will be observed that 105 my improved copy or manuscript holder consists of comparatively few parts that are simple and durable, and such changes in the size, proportion, and minor details of the holder as are permissible by the appended 110 claims may be resorted to without departing from the spirit and scope of the invention.

What I claim, and desire to secure by Letters Patent, is—

1. A copy-holder embodying two supporting-plates slidably connected together, one of which has a bracket at its lower end provided with slots, a follower movable across the upper face of said plates and provided with a pair of slots and lazy-tongs having their upper ends connected in the slots of the follower and their lower ends connected in the slots of the bracket.

2. In a copy-holder, a copy-holding medium adjustable to increase and decrease its 125 length, a folding support, a line-follower hung on said folding support and movable up and down on the copy-holding medium, a main supporting-standard pivotally connected to the copy-holding medium, a movable 130

standard into which said main supporting-standard telescopes, and a cushion fitted in the lower end of the main standard.

3. In a copy-holder, a copy-holding plate, adjustable to increase and decrease its length, combined with a folding support arranged in front of the copy-holding plate, a line-follower carried by said support and movable up and down on said copy-holding plate, a main supporting-standard, and a movable supporting-standard, the main supporting-standard pivotally connected to the copy-holding plate and adapted in one position to telescope in the movable supporting-standard, and in another position to act alone as a support for the plate.

4. In a copy-holder, a copy-holding element embodying two slidably-connected plates, one of which has a supporting-ledge at its lower end, a bracket projecting from said ledge and provided with a pair of slots, a line-follower movable on the copy-holding element and provided with a pair of slots, and lazy-tongs having one end slidably connected in the slots of the line-follower and their other end slidably connected in the slots of the said bracket.

5. In a copy-holder, a copy-holding medium embodying a plate, lugs carried on the rear face of said plate, a substantially inverted-L-shaped main supporting-standard pivotally connected at its upper end to said lugs, a cushion fitted in the lower end of said main supporting-standard, and a portable stand-

ard receiving the cushioned end of said main supporting-standard.

6. In a copy-holder a copy-holding medium embodying a plate, and lugs carried on the rear face of said plate, combined with a portable standard, and a substantially L-shaped main supporting-standard pivotally connected at one end to said lugs and adapted to support said plate when engaged in said portable standard and when resting direct on the support.

7. A copy-holder embodying two slidably-connected plates forming the copy-holding medium, one of said plates having an integral bracket at its lower end, said bracket provided with slots, a line-follower movable on the plates and provided with slots and lazy-tongs pivotally connected at one end in the slots of the line-follower and at the other end in the slots of the bracket.

8. In a copy-holder, a copy-holding medium embodying a plate, a line-follower movable up and down on the plate, and spring-pressed lazy-tongs pivotally attached at their upper ends to the line-follower and pivotally attached at their lower ends to the copy-holding medium.

In testimony whereof I affix my signature in the presence of two witnesses.

FREDERIC CLARKE SHOBERT.
